UNITED STATES PATENT OFFICE.

STEN RUDBERG, OF STOCKHOLM, SWEDEN.

ROCK-DRILLING APPARATUS.

1,319,968.

Specification of Letters Patent.

Patented Oct. 28, 1919.

Application filed November 6, 1917. Serial No. 200,535.

To all whom it may concern:

Be it known that I, STEN RUDBERG, subject of the King of Sweden, residing at Odengatan 90, Stockholm, in the Kingdom 5 of Sweden, have invented certain new and useful Improvements in Rock-Drilling Apparatus, of which the following is a specification.

The present invention relates to rock 10 drilling apparatus, for instance to such machines of this kind, which are driven pneumatically and the invention has for its purpose to increase the effectivity of such apparatus or, more distinctly explained, to 15 cause a material increase of the number of hammer blows, which are delivered per unit of time upon the drill, so that the rapidity of drilling, that is to say, the depth, to which the drill penetrates into the rock per 20 unit of time during the drilling operation is increased.

The rapidity, with which the drilling (the penetration of the drill into the rock) occurs, is of course dependent partly upon 25 the strength of the piston blows and partly on the period of time between each blow and the next. The power of each blow may however not exceed a certain maximum, as the drill then may burst and further the 30 number of blows, which a piston can exert per unit of time is highly limited on account of the fact, that a certain time is required for the piston to perform its reciprocating movement.

35 By using the apparatus, which is the object of the present invention, the drilling can be performed with a rapidity, which is twice or many times greater, than that of the drilling apparatus hitherto known.

40 The invention is substantially characterized by the fact, that the apparatus is provided with two or more pistons, serving as hammers, which are coaxially arranged and alternately deliver blows upon the drill respectively upon an intermediate part (striking block or pin,) abutting against the inner end of the drill.

In the preferred embodiment, the machine is provided with two pistons, the one 50 of which has a tubular shape, while the other piston is movable in the bore of the tubular piston. An embodiment of the invention, adapted on a pneumatically driven rock drilling apparatus, is illustrated in the 55 accompanying drawing.

a indicates the drill, *b* the drill chuck, *c*

the intermediate block, abutting against the inner end of the drill and upon which the piston blows are delivered, and *d* the outer casing or the cylinder of the apparatus. In 60 this latter there are now arranged, according to the present invention, two pistons *e* and *f*, which can deliver blows upon the intermediate block *c*. The one *e* of these pistons is of a tubular cross-section, and 65 thus has an annular working surface. The other piston *f* fits exactly into the tubular piston *e*, so that the two pistons may move freely in the longitudinal direction relatively to each other. Each piston is provided 70 with a head, engaging the inside of the cylinder *d*. These two heads are actuated by the driving fluid in such a way, that they deliver alternate blows upon the intermediate block. *h* and *g* indicate the two 75 cylindrical chambers, in which the piston heads are moving.

It may be easily understood, that by this device a drilling rapidity is effected, which is twice as great, as that which is obtained, 80 when using the drilling apparatus hitherto known, which latter only are provided with a single piston, working against the intermediate block (the drilling tool,) provided the strength of the blows and the stroke 85 speed is the same in both cases.

The pressure air for the power strokes flows through the channel *h* firstly above the piston *f* in the upper part of the cylinder *g* for this piston and causes this latter 90 to exert blows against the intermediate block *c*. When the head of the piston *f* has passed the upper mouth of a channel *n* extending between the cylinders *h* and *g*, the pressure air, now expanded to a certain degree, passes 95 to the cylinder *h* and acts upon the upper side of the head of the piston *e*, so that this latter delivers blows upon the intermediate striking block or pin *c*. The pressure air after having acted upon this piston *e* escapes 100 through the outlet *o*.

The pressure air for lifting the pistons (the return strokes) enters through the channel *l* and flows firstly to the bottom of the cylinder *g*, so that the piston *f* is moved 105 upward (lifted). When this piston *f* during its movement upward has passed the upper mouth of a channel *m*, extending between the lower parts of the cylinders *g* and *h*, the air below the head of the piston *f* flows through said channel *m* to the chamber below the head of piston *e*, so that this 110

latter piston is lifted. When the head of piston *e* has passed the outlet *o* flows the air below the head of said piston out through said outlet. The supply of air to the channels *k* and *l* is regulated by means of a valve device of usual construction in such a way, that the flow of air to *k* is interrupted and the flow of air to *l* begins, when the piston *f* is in its lowest position, while when the piston has reached its upper position, the flow of air to *l* is interrupted and the flow of air to *k* begins.

What I claim is:

1. A pneumatically operated drill including a casing, a drill arranged in the lower end of said casing; an outer piston, an inner piston, passing through the outer piston so that the two pistons when operating deliver blows on different points of the same surface, a head on each of said pistons, means for causing pressure air to act on opposite sides of the heads so as to move the pistons toward and from the tool, a cylinder chamber for each of said piston heads, a transverse wall separating said two cylinder chambers, the stem of the inner piston being tightly guided in said transverse wall.

2. A pneumatically operated drill including a casing, a drill arranged in the lower end of said casing, an outer piston, an inner piston passing through the outer piston so that the two pistons when operating deliver blows on different parts of the same surface, a head on each of said pistons, a cylinder chamber for each of said piston heads, means for causing a quantity of pressure air to first move the inner piston downward and then move the outer piston downward and to escape finally into the atmosphere, and for causing another quantity of pressure air to first move the inner piston upward, then move the outer piston upward and to escape finally into the atmosphere, said two cylinder chambers being

separated from each other through a transverse wall, through which the stem of the inner piston passes.

3. A pneumatically operated drill including a casing, a drill arranged in the lower end of said casing, an outer piston, an inner piston, passing through the outer piston so that the two pistons when operating deliver blows on different points of the same surface, a head on each of said pistons, an upper cylinder chamber for the head of the inner piston, and a lower cylinder chamber for the head of the outer piston, a pressure air inlet channel opening into the upper end of the upper cylinder chamber, a pressure air inlet channel opening into the lower end of said cylinder chamber, a communicating passage extending to the upper end of the lower cylinder chamber from a point lying at some distance below the point at which the first named channel opens into the upper end of the upper cylinder chamber, a second communicating passage extending from a point of the upper cylinder chamber lying some distance below the upper mouth of the first communicating passage to the space of the lower chamber below the head of the outer piston, said two cylinder chambers being separated from each other so that they only communicate through said passages, an outlet from the lower cylinder chamber, which outlet in the lower position of the outer piston communicates with the space above said piston, while said outlet in the upper position of the outer piston communicates with the space below said piston.

In testimony whereof I affix my signature in presence of two witnesses.

STEN RUDBERG.
